DESIGN FOR A CANDLE-PLATE.

59,661.

Specification for Design.

Patented Nov. 15, 1921.

Application filed October 28, 1920. Serial No. 420,290. Term of patent 3½ years.

To all whom it may concern:

Be it known that I, MAX KLEIN, a citizen of the United States, residing at New York, in the county of New York and State of New York, have invented a certain new and ornamental Design for a Candle-Plate, of which the following is a specification, reference being had to the accompanying drawing, forming part hereof.

Figure 1 is a side view, showing my improved candle plate, illustrating a fragmen-

tary portion of the applied ornamentation which, as it is duplicated on the entire circumference, is not shown completely.

Fig. 2 is one-half of a plan view of the same, a portion of the applied ornamentation being shown.

I claim—

The ornamental design for a candle plate, as shown.

MAX KLEIN.
